UNITED STATES PATENT OFFICE.

WILLIAM A. BARNETT, OF LINCOLN, NEBRASKA.

ATTACHMENT FOR GARMENT-TURNING MACHINES.

1,342,937.

Specification of Letters Patent.

Patented June 8, 1920.

Application filed October 26, 1918. Serial No. 259,847.

To all whom it may concern:

Be it known that I, WILLIAM A. BARNETT, a citizen of the United States, and a resident of Lincoln, in the county of 5 Lancaster and State of Nebraska, have invented certain new and useful Improvements in Attachments for Garment-Turning Machines, of which the following is a specification.

10 My present invention relates generally to garment turning machines of the nature described and claimed in my Patent No. 1,273,807, dated July 30, 1918, and is more particularly in the nature of attachments 15 for the garment supporting arms, *i. e.*, both the stationary and movable arms, whereby upon the use of readily mountable and demountable attachments these arms may be adapted to effectively function in connection with both light, medium, and heavy 20 materials, such as the folding or turning of collars of particular design or shape.

In carrying out my invention my aim is to provide different sizes and shapes of 25 points together with means for effectively holding these points in proper relation to the collar supporting arms, examples of which are shown in the accompanying drawings forming a part of this specification, 30 wherein,

Figure 1 is a side view illustrating the practical application of my invention,

Fig. 2 is a plan view of one of the supporting arms shown in Fig. 1,

35 Figs. 3 and 4 are, respectively, a longitudinal and a vertical section taken on lines 3 and 4 of Fig. 2, and

Fig. 5 is a side view illustrating the mode of applying the detachable and interchangeable 40 points.

Referring now to these figures, and particularly to Figs. 1 to 4 inclusive, the collar supporting arms 10 and 11 of a turning machine such as described and claimed 45 in my patent above referred to, are in accordance with my present improvements, provided with detachable interchangeable points 19, which as shown in Figs. 3 and 5 consist of sections of hardened tool steel 50 having a more or less sharpened point 19 and having a flat butt or rear end from which projects a reduced shank 21 which is screw threaded and is screwed into a threaded socket in the end of the arm 55 10, which has a flat face as at 10^a against which the butt end of the point 19 abuts,

the said butt end of the flat end face 10^a of arm 10 being of the same diameter and shape so that a smooth and uninterrupted surface from the extreme point 19 to arm 60 10 is obtained. Each of these points which are interchangeable is provided with a transverse opening 20 adjacent the butt end into which a pin or nail may be inserted to screw or unscrew the point to or from 65 the arm 10.

These points may be of different sizes, that is they may be of varying degrees of sharpness or bluntness, as more blunt points are required for heavy goods such as work 70 jackets, and the like, while on the other hand a blunt point is too coarse for light material to make a perfect point.

It should be further noted that by having the detachable and interchangeable 75 points fit flush as to the periphery with respect to that of the arms, that a perfectly smooth surface is produced from the extreme point and along the arm and thus no obstruction is offered to the ready turning 80 of the collar.

Another feature of my invention as shown in Figs. 1 to 4 inclusive, and which is generally indicated at 12, consists of a plate 13 as best seen in Fig. 2, the front end of 85 which may be rounded or otherwise shaped to fit rounded corners or work having some other shape, and the like, this plate having a curved bearing portion 14 which receives the point 19 and extremity of the supporting 90 arm upon which it is mounted and being provided with openings at opposite sides of said bearing for the reception of clamping screws 15.

Upon the under side of the plate 13 is 95 a somewhat similarly shaped clamping plate 16 which is of materially reduced size however, and into the side openings of which the clamping screws 15 thread so as to securely and immovably clamp the plate 100 13 in connection with the collar supporting arm. In order that the proper relation between the extremity of the supporting arm and the attached point may be arrived at and maintained, the under side of the supporting arm may have a recess 17 as seen in Figs. 3 and 4, into which a projecting portion 18 of the clamping plate 16 fits, as seen in the figure last mentioned, bringing the extremity of the attachment flush 110 with the extremity of the supporting arm as shown in Fig. 3, so that when the clamp-

ing plate is tightened by means of the clamping screws 15, this relation will be maintained during use and accidental displacement avoided.

5. It is of course, to be appreciated that the attachment just described and the detachable points 19 are utilized upon both the stationary arm 10 and the movable supporting arm 11, which co-operates therewith in the operation of the machine, and it is further to be observed that the particular shape of the attachment or interchangeable point may be varied.

10. In this way, I provide for the use of the same supporting arms in connection with the folding of materials of various weights and various different shapes, with the use of but small light attachments capable of being readily mounted and demounted and 20 of speedy interchange.

I claim:

1. A work supporting arm for fabric turning machines having a tapering extremity, a flat supplemental member mounted on said 25 tapering extremity, and means for adjustably securing said supplemental member in position, said means including a recess in said arm, a clamping member provided with a projection adapted to engage in said recess, and means for connecting the clamping member to the supplemental member.

2. A work support for garment turning machines comprising a curved slender arm and a recess on its under side, a sharpened 35 point detachably secured to the end of said arm, a plate resting on said arm and having a curved bearing for said point, and a clamping plate provided with a projection engaging in said recess, for clamping said 40 plate to the arm.

3. A work support for garment turning machines comprising a slender curved arm, a sharpened point detachably secured to the 45 arm so that its surface is flush with the surface of the arm, a plate having a curved bearing portion adapted to fit said point and the adjacent portion of the arm, and a clamping plate shaped to fit the under side of the arm, and means for connecting the 50 clamping plate to said first named plate.

4. A work supporting arm for garment turning machines having a tapering extremity, a detachable supplemental point held thereto in interlocked relation, a plate 55 shaped to fit the work and having a bearing portion partially surrounding the tapering extremity and the supplemental point,

said point serving to partially support the said plate, and means for clamping the aforesaid plate to the tapering extremity 60 and supplemental point, to maintain it in fixed relation thereto.

5. A work supporting arm for garment turning machines having a tapering extremity, a plate shaped to fit the work and 65 having a bearing portion partially surrounding the tapering extremity of the arm, a clamping plate at the opposite side of the extremity of the arm, and clamping screws connecting the two plates. 70

6. A work supporting arm for garment turning machines having a tapering extremity, a plate shaped to fit the work and having a bearing portion partially surrounding the tapering extremity of the arm, a 75 clamping plate at the opposite side of the extremity of the arm, and clamping means connecting the two plates, said tapering arm extremity having a recess and said clamping plate having a projection interfitting the recess for the purpose described. 80

7. In a device of the character described, an arm, a point attached to the arm, and a plate attached to the arm, and partly supported by the point. 85

8. A garment turning device of the character described comprising an arm, a point attached to the arm and a wide flat plate over which the garment is turned, detachably secured to the arm and partly supported by the point. 90

9. A garment turning device of the character described comprising an arm having a threaded opening in its end, a point having a threaded extension adapted to engage 95 in said opening, a wide flat plate over which the garment is turned, detachably secured to the arm, said plate having its forward end shaped to conform to the garment turned and resting on said point. 100

10. A device for turning a flat seam at the rounded corner of a garment comprising a garment supporting arm and a flat plate detachably secured to the extremity of the arm, said plate having a rounded forward edge conforming to the rounded corner of the garment, and a curved bearing portion adapted to fit said arm, and a clamping member beneath said arm for securing the plate to the arm. 105

WILLIAM A. BARNETT.
